UNITED STATES PATENT OFFICE.

THOMAS G. MOUAT, OF BRATENAHL, OHIO.

RETURN-FITTING FOR VAPOR-HEATING SYSTEMS.

1,287,729.

Specification of Letters Patent. Patented Dec. 17, 1918.

Application filed May 17, 1917. Serial No. 169,215.

To all whom it may concern:

Be it known that I, THOMAS G. MOUAT, a citizen of the United States, residing at Bratenahl, in the county of Cuyahoga and 5 State of Ohio, have invented a certain new and useful Improvement in Return-Fittings for Vapor-Heating Systems, of which the following is a full, clear, and exact description, reference being had to the accompanying drawings.

This invention relates to heating systems and has special reference to systems of the low pressure or so called "vapor" type although not necessarily restricted thereto. 15 The objects of the invention are the provision of a return fitting whereby the condensed water can be returned to the boiler from the radiator without meeting any live steam, and without danger of drawing the 20 boiler water into the radiators upon the cooling of the same; the provision of new and improved arrangements for expelling air from the radiators; the provision of arrangements whereby a single conveniently 25 located air valve can be used for a large number of radiators; the provision of means for ejecting condensed water in quantities of considerable volume rather than in a continuous smaller stream whereby erosion of 30 the valves is minimized; while other objects and advantages will become apparent as the description proceeds.

In the drawings accompanying and forming a part of this application I have illustrated my improved return fitting together 35 with a typical heating system employing the same, although it will be understood that the particular constructions and designs here illustrated are only a few out of a large 40 number wherein my invention can be embodied.

In these drawings Figure 1 illustrates a heating system constructed in accordance with my invention; Fig. 2 represents a side 45 elevation of my improved return fitting, Fig. 3 is a vertical sectional view of said fitting corresponding to the line 3—3 of Fig. 4; Fig. 4 is a vertical, sectional view through said fitting corresponding to the 50 line 4—4 of Fig. 3; Fig. 5 is a transverse sectional view corresponding to the line 5—5 of Fig. 3; and Fig. 6 is a perspective view of the vapor passage check valve.

Describing the parts with reference characters, 1 represents the boiler which may be of any suitable type, 2 represents the steam

main and 3 the return main. The boiler is preferably provided with a pressure control apparatus of any suitable type, preferably that illustrated and described in my prior 60 patent issued October 19, 1909, Number 937,686.

5, 5 represents radiators, any number of which may be employed within the scope of my invention, said radiators having inlet 65 pipes 6—6 connected to the steam main 2 and return pipes 7—7 connected to the return main 3. The inlet pipes are preferably connected to the upper portions of the radiators as shown, and governed by inlet 70 valves 8, 8; the return pipes are preferably connected to the lower parts of the radiators as shown, and provided with my improved return fittings 9—9 which will now be described.

75 Each of these return fittings comprises a hollow cylindrical shell 10 having its upper end closed by a screw cap 11 and having its lower end provided with a threaded boss 12 for the attachment of the pipe 7. Formed 80 inside of the shell 10 is a longitudinal partition 13 extending from a point near the top to a point near the bottom of the shell and dividing the same into separate chambers 14 and 15. The chamber 14 is in constant 85 communication with the boss 12 and outlet pipe 7, while the side of the shell adjacent to its upper end is formed with a lateral screw-threaded hollow boss 16 whereby the chamber 15 is maintained in constant 90 communication with the radiator.

95 Adjacent to the lower end of the partition 13 is formed an outlet aperture 17 surrounded on the side adjacent to the chamber 14 by a seat whose plane is inclined to the vertical as shown in Fig. 3; and pivoted upon a horizontal spindle 18 which traverses the chamber 14 above said seat is an arm 19 carrying a valve 20 which cooperates with said seat. The direction of the inclination 100 is such that the valve 20 will be held to its seat by the action of gravity and the force of such holding is proportionate to the slope of such inclination which I have found may conveniently be made approximately 30 degrees, although I do not restrict myself to any particular figure. I have illustrated the outer wall of the chamber 14 as formed with a threaded opening closed by a screw plug 105 21, said opening permitting the insertion of a tool for reaming the valve seat and assembling the valve.

In the partition 13 at a point above this valve I also form a threaded aperture for the reception of the air valve. This device preferably consists of a plate 25 having a 5 threaded boss 26 adapted to screw into the said aperture and formed with a small longitudinal bore 27. Freely hinged outside of the face of this plate is a movable valve member 29, so arranged that its closing portion will normally hang spaced a short distance from the face of the plate 25, but adapted upon the slightest fluid movement toward the radiator to swing toward said plate and close the opening. A tongue 30 10 is preferably employed to limit the opening movement of the valve 29. The return main 3 is provided with a single air escape valve 35, preferably of the automatic type, the same being located in the basement of the 15 building or at any other suitable point.

Upon the operation of a system constructed as above described, the admission of steam into any radiator will displace the air through the bore 27 and chamber 14 into 20 the return main 3 and permit its escape through the valve 35. No air displaced from any radiator can find its way into any other radiator owing to the fact that the air valves 29 prevent such movement. All water 25 condensed in the radiator flows into the corresponding chamber 15 until the pressure due to its height displaces the valve 20. whereupon the chamber quickly empties itself and the valve closes. The location of 30 the steam escape valve separate from and above the water valve tends to prevent the former from becoming clogged or choked and permits it to be made more delicate 35 than would otherwise be feasible.

It will be obvious that many details in 40 design, construction, and arrangement can be made without changing the operation of the device or sacrificing its advantages or departing from my inventive idea and all 45 of such modification I claim as within the purview of my Letters Patent.

Having thus described my invention, what I claim is:

1. In a heating system, a steam radiator, 50 a chambered casing communicating with the lowest part of said radiator and adapted to receive condensed water therefrom, a pipe leading from said casing to the return main, a check valve in said casing, and a normally 55 open air discharge connection also communicating between said radiator and said pipe independently of said water connection, said air connection also having a check valve therein adapted to be closed upon a reverse 60 rush of fluid.

2. In a heating system in combination, a 65 steam radiator, an outlet fitting having its upper part connected to the lowest point of said radiator and comprising an upright hollow casing having a longitudinal partition

thereacross, the lower part of said fitting being connected to the return main, said partition defining two chambers, one of which communicates with the radiator and the other with said main, the lower part of 70 said partition being formed with an aperture, a valve seat surrounding said aperture upon the side adjacent to the second chamber aperture, a check valve in said second chamber coöperating with said seat and normally held in contact with same by gravity, means normally establishing communication between said radiator and said second chamber at a point above said aperture, and a 75 normally open check valve governing said last means adapted to be closed by a rush of fluid toward said radiator.

3. In a heating system, a return fitting for steam radiators comprising a hollow casing having inlet and outlet connections, a 80 partition between said connections and having a pair of apertures therein, one at a higher level than the other and a check valve for each aperture, both of said valves being disposed upon the side of said partition adjacent to the outlet connection, the lower check valve being closed by gravity and the upper valve being opened by gravity.

4. In a heating system, a return fitting for steam radiators comprising a hollow 95 casing having inlet and outlet connections, a partition between said connections and having a pair of apertures therein, one at a higher level than the other, and a check valve for each opening, both of said valves 100 being disposed upon the side of said partition adjacent to the outlet connection, the lower valve being normally closed and the upper check valve being normally open.

5. In a heating system, a return fitting 105 for steam radiators comprising a hollow casing having inlet and outlet connections, a longitudinal partition in said casing dividing the same into two chambers, one of which communicates with the outlet and the 110 other with the inlet, said partition having a pair of apertures therein, one of comparatively large size and adjacent to the outlet, and the other of comparatively small size and adjacent to the inlet, a check valve in the 115 outlet chamber and normally closing the larger aperture and adapted to be opened only by the collection of a considerable amount of liquid in said inlet chamber, and a normally open check valve in said outlet chamber and coöperating with said smaller aperture and adapted to be closed only upon the commencement of a vapor movement from said outlet to said inlet chamber.

6. In a heating system a return fitting for 125 steam radiators comprising a hollow casing having inlet and outlet connections at opposite ends, a longitudinal partition in said casing dividing the same into two elongated chambers, one of which communicates 130

- with the outlet and the other with the inlet, said partition having a pair of apertures therein, one of comparatively large size and adjacent to the outlet, and the other of comparatively small size and adjacent to the inlet, a valve seat surrounding said first aperture and having its plane inclined relatively to the axis of the casing, a check valve in the outlet chamber and normally resting 10 on said seat, and a second check valve in said outlet chamber and hanging loosely in front of said smaller aperture and normally at a small distance therefrom.
7. In a heating system, a return fitting for 15 steam radiators comprising an elongated hollow casing having at one end an outlet opening and adjacent to the other end an inlet opening, a longitudinal partition within said casing and defining two chambers, 20 one of which communicates with each opening, said partition having a pair of apertures therein, one near said outlet opening, and the other near said inlet opening, a pair of check valves in said outlet chamber, one 25 for each opening, the check valve nearest to the outlet being adapted and arranged normally to close its opening and to be displaced therefrom only by a collection of a material amount of liquid in the inlet chamber, 30 and the other of said check valves being adapted and arranged normally to leave its passageway open and to move to closed position only upon the occurrence of gas movement toward the inlet chamber.
- 35 8. In a heating system, the combination with a steam radiator, of a hollow elongated upright casing, the upper end of said casing being attached to the lower part of said radiator and the lower part of said casing being connected to the return main, an upright 40 partition inside said casing and forming a pair of chambers therein one of which communicates with said radiator and the other with said return pipe, said partition having a pair of openings therein, one near 45 the bottom and one near the top, and a pair of check valves in said last chamber, one for each of said openings, the lower check valve being normally closed and the upper check valve being normally open. 50
9. In a heating system, the combination with a steam radiator, of a hollow elongated upright casing, the upper end of said casing being attached to the lower part of said radiator, and the lower part of said casing 55 being connected to the return main, an upright partition inside said casing and forming a pair of chambers therein, one of which communicates with said radiator and the other with said return pipe, said partition having a pair of openings therein, one near 60 the bottom and one near the top, and a pair of check valves in said last chamber, one for each of said openings, the lower part of said partition being inclined whereby 65 its check valve is normally closed, and the upper check valve being spaced slightly from its aperture so as to normally remain open.
- In testimony whereof, I hereunto affix my 70 signature.

THOMAS G. MOUAT.
